DESIGN FOR A GAME APPARATUS

William H. Meiller, Willard D. Wolff, and
Arthur J. Wolff, Buffalo, N. Y.

Application November 8, 1946, Serial No. 134,622

Term of patent 7 years

(Cl. D34—5)

To all whom it may concern:

Be it known that we, William H. Meiller, Willard D. Wolff, and Arthur J. Wolff, citizens of the United States, residing at Buffalo, in the county of Erie and State of New York, have invented a new, original, and ornamental Design for a Game Apparatus, of which the following is a specification, reference being had to the accompanying drawing, forming part thereof.

Fig. 1 is a perspective view of the game apparatus showing our new design.

Fig. 2 is a rear elevation of the same.

Fig. 3 is a side elevation of the same.

Fig. 4 is a top plan view thereof.

We claim:

The ornamental design for a game apparatus, substantially as shown.

WILLIAM H. MEILLER.
